(No Model.)

G. A. OTIS.

OVERFLOW FOR FEED WATER HEATERS.

No. 278,590.

Patented May 29, 1883.

Fig. 1.

UNITED STATES PATENT OFFICE.

GEORGE A. OTIS, OF BUFFALO, NEW YORK.

OVERFLOW FOR FEED-WATER HEATERS.

SPECIFICATION forming part of Letters Patent No. 278,590, dated May 29, 1883.

Application filed November 4, 1882. (No model.)

To all whom it may concern:

Be it known that I, GEORGE A. OTIS, of the city of Buffalo, in the county of Erie and State of New York, have invented new and useful Improvements in Overflows for Feed-Water Heaters, &c., of which the following is a specification.

This invention relates to the construction of the overflow employed in feed-water heaters and similar apparatus for carrying off the excess of water from the surface of the accumulated body of water; and the object of my invention is to construct the overflow in such manner that it will operate to remove the scum and other light impurities which accumulate on the surface of the body of water contained in the apparatus.

My invention consists to that end in providing the mouth of the overflow-pipe with an enlargement or pan, which surrounds the mouth of the overflow-pipe, and serves as a receptacle for the scum and conducts the scum to the mouth of the pipe, which is closed by a suitable float-valve, as will be herein-after fully described, and pointed out in the claims.

In the accompanying drawings, Figure 1 is a section of a feed-water heater provided with my improved overflow. Fig. 2 is a horizontal section in line *x x*, Fig. 1.

Like letters of reference refer to like parts in both figures.

A represents the casing or shell of the heater, which may be of cylindrical or other suitable form, and be constructed of iron, wood, or other suitable material.

B represents the head of the case, and *C* the bottom thereof.

d represents the pipe through which the exhaust-steam enters the apparatus, and *D* an enlarged mixing-chamber which forms a continuation of the pipe *d*, and which depends from the cover *B* into the shell of the heater.

e represents the pipe through which the feed-water enters the apparatus, and *E* represents a spray-nozzle, which is secured to the end of the pipe *e* within the chamber *D*, and which serves to distribute the water in a spray and bring the same in intimate contact with the exhaust-steam which enters through the

pipe *d*, both the steam and water escaping from the mixing-chamber through the open lower end thereof into the shell *A*.

F represents the vapor-escape pipe, which is connected with the upper portion of the apparatus. All of these parts may be of any suitable and well-known construction.

g represents the overflow-pipe, secured in an upright position in the lower head or bottom, *C*, and extending upwardly into the shell *A*.

G represents the scum-pan, which surrounds the upper end of the overflow-pipe, and which is secured to said pipe by means of a set-screw, *h*, or by a screw-thread or other suitable means.

I represents the valve, which is applied to the upper end of the overflow-pipe *g* within the scum-pan *G*. The valve is attached to the arm *j* of a float, *J*, which floats upon the surface of the body of water, and which serves to open the valve when the water-level rises above the desired point. The arm *j* is pivoted to the pan *G* at *l*, and provided with a nose, *m*, which limits the opening movement of the valve. The water which has become heated by contact with the exhaust-steam accumulates in the lower portion of the apparatus, and the scum and other light impurities contained in the water rise to the surface and pass over into the pan *G*, which latter retains the scum and prevents the same from flowing back into the body of water and mingling therewith. The float is preferably so arranged that the valve will open and discharge the scum before the clear water rises to the upper edge of the scum-pan.

k represents the pipe through which the heated water passes from the lower part of the shell *A* to the feed-pump or other device, whereby it is conveyed to the boiler or other apparatus in which it is desired to be used. If the supply of water to the apparatus exceeds the quantity of water which is withdrawn through the pipe *k*, the excess of water is discharged through the overflow-pipe *g*.

I claim as my invention—

1. In a feed-water heater, the combination, with an overflow-pipe, *g*, of a scum-pan, *G*, surrounding the mouth of said pipe, a valve, *I*, seated in the overflow-pipe, and a float, *J*,

attached to said valve, substantially as set forth.

2. The combination, in a feed-water heater, of a steam-pipe, *d*, provided with a mixing-chamber, *D*, a water-supply pipe, *e*, provided with a spray device, *E*, an overflow, *g*, provided with a scum-pan, *G*, a float-valve, *I*,

seated in the overflow-pipe, and a pipe, *k*, through which the heated water passes from the apparatus, substantially as set forth.

GEORGE A. OTIS.
